UNITED STATES PATENT OFFICE.

PAUL MAUSER, OF OBERNDORF-ON-THE-NECKAR, GERMANY.

PISTOL-BULLET.

1,053,845.

Specification of Letters Patent. Patented Feb. 18, 1913.

Application filed October 26, 1910. Serial No. 589,236.

To all whom it may concern:

Be it known that I, PAUL MAUSER, privy commercial councilor, a subject of the King of Wurttemberg, residing at Oberndorf, in the Kingdom of Wurttemberg, Germany, have invented certain new and useful Improvements in Pistol-Bullets, of which the following is a full, clear, and exact description.

10 It has latterly been recognized that it is not really necessary that effective action should be had at long ranges with pistols and the like, and that the most advantageous ammunition is that which exerts its 15 action most intensively at short ranges, such as occur when fighting at close quarters.

The present invention relates to a pistol bullet which is specially designed for attaining the maximum velocity or maximum 20 effect at relatively short ranges, say about 100 meters from the muzzle of the weapon, the formation of this bullet being such that within this distance an exceedingly flat trajectory, that is to say a point blank shot, 25 is obtained.

The pistol bullet in accordance with the invention is illustrated in section many times enlarged in the accompanying drawing.

30 The bullet is of special large diameter (11 mm. for example) and consists of the bullet casing or envelop *m* and the core *k*, the latter being made of light metal such as aluminium.

35 The bullet as a whole is formed conically both in its front portion *a* and in its rear portion *c*; between these two parts a middle cylindrical guide portion *b* is situated and in order to obtain a flat trajectory the distribution of the mass is so arranged that the 40 center of gravity is located in the cylindrical guide portion in proximity to the front part *a* of the bullet. The regulation of the position of the center of gravity in this way

is facilitated in particular owing to the fact 45 that the rear end of the core of the bullet is indented and according to the greater or smaller depth of the indentation the center of gravity is located more or less in the front end of the guide part. 50

In order to increase the penetrative power 55 the envelop of the bullet can be reinforced at the point, for example by a lead insertion *d* as shown in the drawing.

By means of the construction and form 55 described above the bullet meets all the requirements, as regards obtaining the highest efficiency from the weapon when fighting at close quarters, which at the present time are made of such firearms in technical 60 military circles.

With this bullet, which is light relatively to its diameter, (a bullet of a caliber of 11.0 mm. weighs 14 grams with an insertion of antimony lead for example, while a similar bullet with an aluminium insertion weighs only 5.4 grams) a high initial velocity and consequently a flat trajectory can be obtained. 65 As a result a considerably higher percentage of hits can be secured with pistols within 70 their firing range, while owing to the lightness of the bullet the recoil is greatly reduced.

What I claim as my invention and desire to secure by Letters Patent is: 75

A bullet for pistols comprising a metallic casing and a core of light metal and having a central cylindrical guide portion of a diameter of about half the length of the bullet and conical end portions and a reinforcement at the front end of the bullet. 80

In witness whereof, I have hereunto signed my name in the presence of two subscribing witnesses.

PAUL MAUSER.
